UNITED STATES PATENT OFFICE

ROBERT ROGERS, OF DALLAS, TEXAS, ASSIGNOR TO HENRY CHILTON ROGERS, OF DALLAS, TEXAS

AUTOMATIC WATER HEATER CONTROL VALVE

Application filed April 24, 1931. Serial No. 532,577.

This invention relates to certain new and useful improvements in automatic water heater control valves.

The primary object of the invention is to provide an automatic water heater control valve wherein the usual piston or plunger valve equipped with packing and working in a cylinder for the operation of a gas valve is eliminated and a bellows construction or expanding tube substituted therefor to render the control valve leak-proof in operation.

A further object of the invention is to provide a valve structure of the foregoing character wherein a valve casing housing an expandible tube or bellows-like member responsive to pressures has the upper wall of the bellows of dished formation to permit full expansion of the bellows in the presence of stencil protrusions or the like usually formed on the closure cap for valve casings of the general character disclosed in the instant art.

With the above and other objects in view that will become apparent as the nature of the invention is better understood, the same consists in the novel form, combination and arrangement of parts hereinafter more fully described, shown in the accompanying drawing and claimed.

In the accompanying drawing showing a preferred embodiment of the invention, the automatic water heater control valve is shown in vertical section, disclosing the waterpressure operated control valve and the lower gas valve operated thereby.

In the present invention, there is provided a water pressure operated valve device operatively associated with a gas valve to effect opening movement of the latter upon operation of the water valve, the water valve comprising a casing 1 arranged above the casing 2 of the gas valve with the two casings connected by a U-shaped bracket 3 that has side arms 4, each provided with an opening 5 therein through which externally threaded bosses 6 carried by the bottom wall 7 of the valve casing and the top wall 8 of the gas valve casing extend, each casing being retained in position upon the bracket by a nut

9 threaded on the boss for clamping the casings in position.

The water control valve casing 1 is of cylindrical formation and is closed at its upper end by a removable cap 10 having a depending externally threaded annular flange 11 spaced inwardly of the peripheral edge of the cap and having internal threaded engagement with the upper end of the casing 1, the outer edge of the cap resting upon the upper edge of the casing with the gasket interposed between the cap and casing to render the casing water-tight. One side of the casing, adjacent its upper end has a water inlet connection 12 to be placed in communication with a service supply and the diametrically opposite side of the casing 1 adjacent its lower end has a water outlet connection 13 to be placed in communication with a water valve or spigot.

The valve mechanism within the casing 1 includes a cylinder 14 open at its upper and lower ends with depending spaced lugs or feet 15 for spacing the lower end of the cylinder from the bottom wall 7 of the casing, the cylinder being of a height to terminate below the water inlet 12. The cylinder 14 is of less diameter than the casing 1 and is concentrically positioned therein, and to retain the cylinder against movement within the casing, the outer side of the upper edge thereof is beveled as at 16 to permit wedging reception of the relatively soft metal, rubber or composition gasket 17 received between the beveled face 16 and the inner face of the casing 1. A side port 18 is formed in the cylinder 14 in alignment with the casing outlet 13 and is of a diameter less than the diameter of said outlet for purposes presently to appear.

An expanding tube or bellows 19 is disposed within the cylinder 14, being concentric therewith and spaced from the walls of the cylinder, with its lower end soldered or otherwise secured as at 20 with an inwardly directed annular shoulder 21 carried by the lower end of the cylinder 14, the bellows 19 being of a normal height to terminate at a point adjacent the upper end of the casing 1 above the cylinder 14 and inlet 12. A

comparatively deep cup-shaped closure 22 is provided for the upper end of the bellows 19 and has an outwardly directed upper edge flange 23 to which the upper end of the bellows 19 is soldered or otherwise secured, while the bottom wall 24 of the closure member 22 extends a considerable distance downwardly in the bellows 19. In valve casings of this general character, the closure cap 10 therefor usually carries a well defined central projection 25 projecting downwardly therefrom and by the provision of the cup-shaped closure 22 for the upper end of the bellows 19, the latter is permitted to expand its complete length of normal movement without contacting the casing cap 10 or the usual projection 25 depending therefrom. An operating rod 26 having threaded engagement 27 with the bottom wall 24 of the cup-shaped member 22 depends through the boss 16, the latter being of cup formation and containing packing 27 engaged by a follower gland 28 through which the rod 26 extends as illustrated.

The casing 2 for the gas valve has a cross-partition 29 therein with a central valve opening 30 closed by a valve 31 that is retained upon its seat by the spring 32 interposed between the valve 31 and the bottom wall or closure plug 33 of the casing 2. Said casing having a gas inlet connection 34 in a wall thereof below the partition 29 and a gas outlet connection 35 in a wall above the partition 29. An operating rod 36 for the valve 31 extends through the upper wall 8 of the casing 2 and bushing 6, the latter being of cup formation and containing packing 27a engaged by the follower gland 28a, the upper end of the gas valve operating rod 36 terminating in spaced relation to and adjacent the lower end of the operating rod 26.

When the hot water spigot to which the outlet 13 of the valve casing 1 is connected, is closed, water pressure within the casing 1 is equalized at the inner and outer side of the bellows 19, water occupying the area within the casing 1, communication being established between the inner and outer sides of the bellows by the opening 18 in the cylinder 14 at the lower open end of the cylinder that is spaced from the bottom wall 7 of the casing, the bellows 19 remaining in its normal position with the cup shaped closure member 22 for the upper end of the bellows at its limit of upward movement and unaffected by the projection 25 upon the casing cap 10. When the spigot is opened, water flows from the casing 1 through the outlet 13 and as said outlet is of considerably greater area than the cylinder outlet 18, pressure within the casing is increased as the flow through outlet 18 is slower than the flow through outlet 13, resulting in compression of the bellows 19 and downward movement

of the rod 26 to operate the gas valve rod 36, to permit the flow of gas to a burner. So that water may flow from the spigot with increased pressure, a by-pass opening 37 is provided in the bottom wall 24 of the cup-shaped member 22 and is normally closed by a conical valve head 38 which carries a depending stem 39, the lower end of which is movable into engagement with the bottom wall 7 of the casing 1 for unseating the conical valve 38 to allow an additional supply of water to flow through the by-pass opening 37 and escape to the lower open end of the bellows 19 and cylinder 14 and flow through the outlet 13 to the spigot, a cross pin 40 carried by the lower end of the pin 39 retaining the conical valve 38 in assembled relation to the cup-shaped member 22. When the spigot is closed, water pressure in the casing 1 is again equalized at the inner and outer sides of the bellows 19 which allows the bellows to expand for elevating the rod 26 to disengage the latter from the gas valve operating rod 36, the gas valve 31 being then closed by the spring 32.

From the above detailed description of the invention, it is believed that the construction and operation thereof will at once be apparent, and while there is herein shown and described the preferred embodiment of the present invention, it is nevertheless to be understood that minor changes may be made therein without departing from the spirit and scope of the invention as claimed.

I claim:

In a water heater the combination with the water heater control valve casing having inlet and outlet ports, of a cylinder located therein, and spaced from the wall of the casing and of less diameter than the casing, and a detachable soft metal gasket between the inner wall of the casing and the outer wall of the cylinder, the latter being beveled at its upper edge and the gasket correspondingly beveled.

In testimony whereof I affix my signature.

ROBERT ROGERS.
